SCARF

Abraham S. Morrow, Brooklyn, N. Y.

Application November 14, 1950, Serial No. 12,977

Term of patent 3½ years

(Cl. D3—12)

To all whom it may concern:

Be it known that I, Abraham S. Morrow, a citizen of the United States, residing at Brooklyn, New York, in the county of Kings, and State of New York, have invented a new, original, and ornamental Design for a Scarf, of which the following is a specification, reference being had to the accompanying drawing, forming part thereof.

In the drawing:

The figure is a plan view of a quarter section of a scarf, showing my new design, said quarter section being duplicated at each corner thereof.

I claim:

The ornamental design for a scarf, as shown and described.

ABRAHAM S. MORROW.
